UNITED STATES PATENT OFFICE.

CLAUDE U. TYRRELL, OF CHICAGO, ILLINOIS.

MONOPLANE FLYING TOY.

1,190,343.

Specification of Letters Patent. Patented July 11, 1916.

Application filed July 20, 1914. Serial No. 851,840.

To all whom it may concern:

Be it known that I, CLAUDE U. TYRRELL, a citizen of the United States, and resident of the city of Chicago, in the county of Cook and State of Illinois, have invented certain new and useful Improvements in Monoplane Flying Toys, of which the following is a full, clear, and exact specification.

This invention relates to improvements in monoplane flying toys, which on being manually projected upwardly in the air, gradually glide to the ground, and in which so far the wings or planes and the tail or rudder are rigidly secured in their outspread flying position to their connecting support, with result that the height and distance to which the monoplane can be projected is accordingly limited, as is also variations in the direction of its glide.

The prime object of this invention is a monoplane flying toy, the wings of which are foldable and in such a manner that the device as a whole may be projected to a comparatively great height or distance with the employment of a minimum amount of propelling force consistent therewith before the folded wings are spread to their operative position for producing the downward gliding of the monoplane.

A further object of this invention is to have the wings of the toy monoplane foldable so compactly that it may be projected to a great height, provided with means for automatically spreading the wings as soon as the projecting force has ceased.

Another object of my invention is the monoplane flying toy provided with an adjustable tail or rudder which may be adjusted not only to vary the predetermined angle of its descent, but to cause the monoplane to descend spirally and in smaller or greater spirals either to the right or to the left, as may be desired.

With these ends in view my invention finds embodiment in certain features of novelty in the construction, combination and arrangement of parts by which said objects and certain other objects are attained, all as hereinafter described with reference to the accompanying drawing, and more particularly pointed out in the claims.

In said drawing: Figure 1 illustrates in top plan view a monoplane flying toy in which my invention finds embodiment, Fig.

2 is a perspective view showing the wings of the monoplane partly folded, Fig. 3 is a detailed perspective more clearly showing the devices by which the folding wings are pivoted to the backbone and the devices by which they are automatically opened to their operative position, Fig. 4 is a side elevation, partly in section, with the wings closed and means by which the monoplane is projected into mid air, Fig. 5 is a top plan view of the same with the wings in their folded or closed position, and Fig. 6 a detailed perspective of the slideable clip for supporting the spring for automatically opening the wings to their outspread flying position.

Similar characters of reference indicate the same parts in the several figures of the drawing.

The backbone of my monoplane flying toy consists of a bar 7, the forward end 8 of which is somewhat thickened and more or less pointed, and provided with an inclined surface 9 for the purpose hereinafter described, to the rear end of which bar is secured a sleeve 10 providing a socket end piece 11 receiving a short bar 12, to which is secured the tail or rudder 13 and for which purpose the bar 12 may be split to receive the rudder, then rigidly secured thereto by means of tacks or screws 14, the rudder being preferably of thin, stiff pasteboard and somewhat pear-shaped in form, but may be of any other form or material adapted for the purpose.

At the forward end of the backbone are flat bars 15 and 16, the adjacent ends of which overlap each other and have their bearings against the inclined surface 9 of the beak, a screw or bolt 17 passing through the overlapping ends of the two bars into the beak of the machine whereby the bars are pivoted. The ends of the bars 15 and 16 being at each side of the beak bent upwardly to an inclined position and having their outer ends extended by means of other and straight bars 18 and 19 secured by a rivet or screw bolts 20, thereby form the front edge of the monoplane and the supports for the wings 21, 22, which in their outstretched position, shown in Fig. 1, extend from each side of the backbone to the bars 18 and 19.

The wings 21 and 22 are made of somewhat stiff paper and may be in two pieces, but in practice are in one piece folded at the

center width as indicated at 23, Fig. 2, with the fold projected through a slot 24, shown in Fig. 2 and indicated by dotted line in Fig. 1, between which double fold and the front edges of the wings so formed are a number of folds 25, 25 on lines radiating from a center, so that when the bars 18 and 19 are swung to a position parallel with the backbone the wings may be folded against the backbone; that is to say, to the position shown in Fig. 5.

The outer edge of the wings are preferably formed on the arc of a circle, but may be of other form, and the inner or forward edges cut away on an arc of a circle as indicated at 26 in Figs. 1 and 3, in order that it may not furnish an obstruction to the devices for automatically opening the wings to their outspread condition as hereinafter described.

At the forward end of the backbone is a longitudinal groove 27 receiving a form and guideway for the clip plate 28, provided with an upright lug 29 on which is secured a spring coil 29 provided with projecting arms 30 and 31, the ends of which are secured to the pins or screw bolts 20.

The clip plate 28 is provided at each side of its upright 29 with flanges 32 and 33 bent in opposite directions and resting upon the top of the backbone, which forms a track therefor, the clip being prevented from a vertical movement by flange 34 embracing the underside of the backbone.

In the position shown in Fig. 1 the wings are normally distended through the force exerted by the spring arms and in their operative position form an imparting and gliding movement to a monoplane in mid air.

As a means for projecting the monoplane into mid air the underside of the backbone is provided (see Fig. 4) with a catch 35 adapted to be engaged by a looped string 36 secured to a resilient single or folded strip 45 of rubber 37, the opposite end of which, not shown, may be fastened to a stick or handle, not shown, so that, for example, on holding the monoplane with its wings folded in one hand, by grasping between the fingers the underside folds, and in the other hand the stick, and then following the stretch of the rubber and suddenly letting the monoplane loose, it will be projected upwardly in the desired direction, the elevation depending upon the strength of the strip of rubber and therefore the force with which the monoplane is impelled. In other words, the wings will be closed by air pressure during its ascent and until the impelling force has been substantially expended and the air pressure is sufficient to make the wings folded, whereupon the wings will be quickly spread to their full extent by the action of the air pressure laterally in opposite directions against the folded wings, and for which pur-

pose the folds in the wings should be sufficiently wide.

The advantage of providing a monoplane flying toy with foldable wings is by folding them against their backbone they are maintained in a direct path of flight and line of force exerted against the backbone and are thereby held by air pressure in such a position as to offer the least possible resistance to the force projecting the monoplane into mid air; that is to say, either vertically, obliquely or substantially in a horizontal plane as may be from an elevation with good effect.

Immediately the wings are expanded, a gliding, downward movement is imparted to the monoplane through the uplifting force of the air beneath, the direction of which movement may be predetermined by adjusting or turning the tail or rudder in the socket 11 accordingly. For example, if the rudder is adjusted to a plane horizontal with that of the wings, the monoplane will descend along the lines of a straight, inclined plane, continuing in the same direction; whereas if the rudder be turned at an angle to the plane of the outstretched wings it will gradually soar to the earth, either to the right or to the left as the rudder may be set, at an oblique angle to the surface of the wings. On the other hand, if the rudder be turned until its surface is at a right angle to that of the wings, the monoplane will dart in almost a vertical line to the earth. Again, as the oblique angle of adjustment of the rudder is shifted, so will the length of the spirals' descent be increased or diminished.

My invention is not limited to the specific means shown and described for projecting the monoplane into mid air, nor specific devices by which its foldable wings are stiffened at their forward edges, nor the specific devices by which they are automatically spread quickly following the expenditure of the force projecting the device into mid air, nor to the specific materials of which it is composed.

Instead of employing the rubber sling shot before described for projecting the monoplane, it is obvious that it might be projected by means of a cross bow or similar device.

Having described my invention, what I claim and desire to secure by Letters Patent is:—

1. A monoplane flying toy comprising in combination a backbone, foldable wings pivoted thereto, a coiled spring, arms pivoted respectively to said wings, and means slidably connecting said spring and arms with the backbone, whereby said wings yieldingly unfold from the opposite sides of a fixed line therethrough extending longitudinally of the backbone.

2. A monoplane flying toy comprising in combination a backbone, foldable wings pivoted at one end thereof, a spring, the ends of

which are respectively pivoted to said wings, a clip for and slidably connecting said spring with the backbone.

3. A monoplane flying toy comprising in combination a backbone, foldable wings pivoted to and toward one end thereof, a spring slidably connected with the backbone having its opposite ends pivoted respectively to said wings, and a rudder adjustable on the opposite end of said backbone, and whereby the direction of the glide of the monoplane is predetermined and fixed throughout its flight.

4. A monoplane flying toy comprising in combination a backbone, foldable wings pivoted thereto, a spring slidably connected

with the backbone at one end thereof, an adjustable rudder at the opposite end thereof, a catch projecting from the underside of the backbone about the middle of the length thereof, adapted for releasably holding an elastic sling for projecting the monoplane in mid-air when held by a grip well toward the rear end thereof.

In witness whereof, I have hereunto set my hand and affixed my seal, this 14th day of July, A. D. 1914.
